[57] CLAIM

The ornamental design for a welding machine, as shown
and described.

DESCRIPTION

FIG. 1 is a view in perspective of a welding machine
showing my new design;

FIG. 2 is a top plan view thereof, the bottom being
unornamented;

FIG. 3 is a side elevational view taken from the right of
FIG. 1;

FIG. 4 is a side elevational view taken from the left of
FIG. 1;

FIG. 5 is a front elevational view, and

FIG. 6 is a rear elevational view.

FIG. 1

FIG. 2

FIG. 3

FIG. 4

FIG. 5

FIG. 6
